H. M. Wilson
Attorney.

UNITED STATES PATENT OFFICE.

HARRY M. WELLS, OF OMAHA, NEBRASKA.

BURIAL-VAULT.

1,351,313.

Specification of Letters Patent. Patented Aug. 31, 1920.

Application filed June 10, 1919. Serial No. 303,088.

To all whom it may concern:

Be it known that I, HARRY M. WELLS, a citizen of the United States of America, residing at Omaha, in the county of Douglas and State of Nebraska, have invented certain new and useful Improvements in Burial-Vaults, of which the following is a specification.

The primary object of the present invention is to provide a burial vault adapted for the reception of a casket in which the vault is of substantially the same form as a casket adapted to receive the same and embodying a removable cover section that is sealed thereon.

A further object of the invention is to provide a burial vault of box-like construction having a cover wall removable therefrom with coöperating inclined flanges carried by the body portion of the vault and the cover adapted properly to center the cover upon the structure with a snug fit and subsequently rendering the same air-tight by a filling of plastic material about the joint.

With these general objects in view, the invention consists in the combination and arrangement of parts hereinafter described in connection with the accompanying drawing, and in which like characters of reference designate corresponding parts throughout the several views,

Figure 1 is a cross sectional view of a burial vault constructed in accordance with the present invention,

Fig. 2 is a fragmentary cross sectional view on an enlarged scale, of a portion of the joint between the body and cover and

Fig. 3 is a detail perspective view of a portion of the upper edge of the body portion.

The object of the present invention being to provide an air-tight cover for a burial vault, the present invention resides more particularly in the specific construction of the joint between the vault body and cover, in which the body portion 5 is of the usual oblong construction, being formed of such material as concrete or the like and having a wire reinforcing element 6 embedded therein for purposes of reinforcing and strengthening the walls and bottom thereof. The upper edges of the side and end walls of the body 5 are plain upon the inner faces 55 while the outer faces thereof are of increased

cross sectional area to provide supporting shoulders 7 for a cover 8. The detailed construction of the shoulder is shown more clearly in Fig. 3 in which there is provided a channeled seat 9 formed by cutting away the outer portion of the shoulder 7 and providing an outwardly positioned flange 10 and an inner flange 11 forming a continuation of the walls of the body, while the outer face of the flange 11 is inclined as at 12, as shown more clearly in Fig. 2 for purposes presently to appear.

The cover 8 is of arched formation and includes a depending peripheral flange 13 that is adapted to be received on and supported by the channeled seat 9 while the inner face of the flange 13 is inclined as at 14 and with the cover in position on the body 5, the opposed inclined walls 12 and 14 substantially frictionally engage so as to provide an air-tight closure for the vault.

In positioning the cover 8 upon the body 5, the inclined walls cause the cover to center properly on the body portion 5 so that the lower edges of the flanges 13 engage throughout their length the channeled seat 9. When so arranged, a plastic filling 15 is placed upon the seat 9 outwardly of the flange 13 and inwardly of the flange 10 to fill the space created therebetween and effectively to seal the cover upon the body to the exclusion of air entering the body. With this construction, a burial vault is provided in which the cover is self-centered by the formation of the opposing contacting walls of the cover and body portion, while in addition to the walls engaging throughout their lengths, forming an air-tight closure, the plastic filling further prevents the admission of air to the body.

What I claim as new is:—

1. A burial vault comprising a body portion, a shoulder formed upon the upper edge thereof, the upper face of the shoulder being cut away to provide a flat seat with upstanding inner and outer flanges, the outer flange being shorter than the inner flange, the outer face of the inner flange being flat throughout its length and inclined outwardly and downwardly, and a cover having a depending flange resting flatly on said seat and supported thereby, the inner face of the cover flange being flat throughout its length and inclined coincident to and contacting with the outer face of the inner shoulder

flange body contacting the same over its entire surface, the outer face of the cover flange being vertical and spaced from and parallel with the inner face of the outer shoulder flange of the body, and a plastic filling material for sealing the cover flange on the shoulder positioned on the seat between the inner face of the outer shoulder flange and the outer face of the cover flange.

10 2. A burial vault comprising a body por-

tion, a shoulder formed upon the upper edge thereof, the upper face of the shoulder being cut away to form a channel seat, a cover having a depending flange flatly resting on the bottom wall of the channel seat, and a 15 plastic filling for sealing the cover on the shoulder positioned on the seat outwardly of the cover flange.

In testimony whereof I affix my signature.

HARRY M. WELLS.
